FLORAL DISPLAY STAND

Filed Jan. 13, 1931

Fig.1.

UNITED STATES PATENT OFFICE

THOMAS L. KNIPE, OF KOKOMO, INDIANA

FLORAL DISPLAY STAND

Application filed January 13, 1931. Serial No. 508,507.

This invention relates to flower displaying stands and particularly to stands adapted to support containers for flowers in a variety of positions to obtain varied displays.

5 An object of the invention is to provide a device of this character which is simple and hence inexpensive in construction which will support a maximum number of flower containers and which may be readily set up 10 in the house or in the open as for example in a cemetery.

Referring to the accompanying drawing, which is made a part hereof and on which similar reference characters indicate similar 15 parts,

Figure 1 is a perspective view of the device,

Figure 2 is a similar view showing containers supported on the stand, and

20 Figure 3 is a section showing how certain containers are secured in position.

In the drawing numeral 10 indicates a looped portion of the stand, the ends of which extend down and are secured at 11 and 12 25 by spot welding or similar fastening means to an oblong loop 13. A loop 14 is secured as by spot welding at 15 and 16 somewhat above the ends of the loop 10 so as to provide parallel portions 17 and 18 which serve as 30 posts for supporting the loop 14 spaced above the loop 13. Legs 19 and 20 are secured at their upper ends as at 21 to the side of the loop 14 and also are secured at 22 to a side of the loop 13. A post 23 likewise is se-

35 cured at its upper and lower ends to the sides of the loop 14 and 13 opposite the legs 19 and 20. A bar 24 is positioned longitudinally of the loop 13 at about its middle portion and secured thereto and this bar has its 40 outer ends extending out beyond the ends of the loop and preferably slightly bent around toward the front of the stand as shown at 25. A bar 26 is secured to the sides of the legs 19 and 20 to brace them and to

45 serve as a support for a triangular bracket 27. The bracket 27 has its ends looped around the bar 26 at 28 to provide a hinged connection and the opposite end or vertex of the triangle consists of a loop 29 through which 50 the back leg 30 passes, the upper end of this

leg being hinged to the back side of the loop 13 at 31. A cross bar 32 serves in connection with the bar 26 to support a depending U-shaped bracket 33 which is secured at its ends to the bars 32 and 26 respectively. The 55 bracket 33 is adapted to support a flower pot 34 as shown in Figure 2, the pot resting upon the bracket.

In operation flower containers 35 are positioned within the loop 14 and rest upon the 60 rod 24. Additional containers 36 are positioned outside of the loops 13 and 14 and rest upon the ends 25 of the bars 24. In order to hold the outside containers in position they are secured as at 37 adjacent their tops to 65 one of the inside pots 35. The containers may be secured in any manner as by rivets, as shown or they may be detachably secured together by slipping clips over the edges of 70 adjacent pots. The containers 34 and 35 may be of any suitable construction and of any appropriate material adapted for the purpose.

While the invention has been described as 75 useful for supporting containers for cut flowers obviously it is not limited to this use. It may be adapted for use as a support for pots containing growing plants and flowers or any other purposes for which it may be 80 found suitable.

When in use the stand may be set upright or made to lean back against a support. When positioned out of doors the legs may be stuck in the ground to firmly support the stand as when used as a flower stand in a 85 cemetery. In order to exhibit the flowers better it may be desired to tilt the pot 34 forward to incline the flowers therein toward the front. This may be done by swinging the rear end of the bracket 27 upwardly. 90 This moves the hinged leg 30 inwardly. When stuck in the ground this leg will hold the bracket 27 in its adjusted angular position. By folding bracket 27 toward legs 19 and 20 leg 30 will come close to the same plane as legs 19 and 20 and thus provide for a 95 substantially flat package for shipping or storing purposes.

It will be obvious to those skilled in the 100 art that various changes may be made in my

device without departing from the spirit of the invention and therefore I do not limit myself to what is shown in the drawing and described in the specification but only as indicated by the appended claims.

Having thus fully described my said invention, what I claim as new and desire to secure by Letters Patent, is:

- 10 1. A flower display stand comprising a pair of loops having a pair of legs secured thereto, a loop secured to said first named loops to hold them in spaced apart position, said loop serving as a handle for the stand, a third leg hinged to the lowermost of said loops, a bracket slidably securing the leg but spacing it apart from the pair of legs, substantially as set forth.
- 20 2. A flower display stand comprising a pair of loops having a pair of legs secured thereto, a loop secured to said first named loops to hold them in spaced apart position, a third leg hinged to the lowermost of said loops, a bracket slidably securing the leg but spacing it apart from the pair of legs, and a bar positioned in the lowermost of said loops, said bar serving as a support for flower containers, substantially as set forth.
- 30 3. A flower display stand comprising a pair of loops having a pair of legs secured thereto, a loop secured to said first named loops to hold them in spaced apart position, a third leg hinged to the lowermost of said loops, a bracket slidably securing the leg but spacing it apart from the pair of legs, and a bar positioned in the lowermost of said loops, said bar serving as a support for flower containers, said bar having its ends extending beyond the said lower loop, said ends serving to support additional flower containers, substantially as set forth.
- 40 4. A flower display stand having a frame-like receptacle at its upper end for flower containers composed of a pair of loops spaced apart and having a bar positioned across the lowermost loop, said bar serving to support flower pots, a pair of legs rigidly secured to said loops, an additional leg hinged to one of said loops, a bracket hinged to said pair of legs and slideable on said hinged leg, said bracket having a depending loop adapted to receive and support a flower container, substantially as set forth.
- 50 5. A floral stand comprising a receptacle adapted to contain flower containers, a pair of legs rigidly secured to said receptacle, a third leg hingedly connected to said receptacle, a bracket hinged to said pair of legs below said receptacle and slidably attached to said third leg to permit adjustment of the bracket, said leg and bracket being provided with a flower container which may be positioned therewith at a desired angle by adjustment of the bracket and third leg, substantially as set forth.
- 60 6. A flower support comprising a frame

composed of a plurality of wires secured together, said frame comprising a receptacle adapted to contain a plurality of flower containers, a pair of legs rigidly secured to said receptacle, a single leg hinged to said receptacle, a brace hinged to said pair of legs and slidably connected to said third leg, a container receptacle in said brace, said legs being adapted to be stuck in the ground to provide a support for the containers, said brace and container being adjustable to permit positioning of this flower container at various angular positions, substantially as set forth.

In witness whereof, I have hereunto set my hand at Kokomo, Indiana, this 10th day of January, A. D. nineteen hundred and thirty-one.
